UNITED STATES PATENT OFFICE.

ALBERT E. F. MOONE, OF WYOMING, OHIO, ASSIGNOR TO THE PHILIP CAREY MANUFACTURING COMPANY, A CORPORATION OF OHIO.

PROTECTIVE COVER FOR ARTICLES.

Application filed June 14, 1920. Serial No. 388,765.

To all whom it may concern:

Be it known that ALBERT E. F. MOONE, citizen of the United States, and a resident of and whose post-office address is Wyoming, county of Hamilton, State of Ohio, has invented an Improvement in Protective Covers for Articles, of which the following is a specification.

My invention relates to an improvement 10 in covers, more especially temporary covers for products such as rolls of felt, paper, asbestos paper, prepared roofing and similar products where the edges of the products, formed at the junction of the ends of the 15 roll and the sides of the roll, are liable to become, and do, frequently become damaged. In transporting such materials from place to place the edges of the outer convolutions of the roll are frequently damaged by 20 the roll being dropped or coming in contact with other articles or with surrounding building structures, etc., with the result that the outer convolutions very often have to be cut away and go to waste.

25 My cover is adapted to fit rolls of different length and different circumference so as to protect the edges thereof from damage, while at the same time being so constructed that it may readily be applied to the product or removed therefrom.

30 My covers are made preferably of a flexible material and are so constructed that they are very readily applied to the rolls and with equal readiness removed therefrom. While I have shown and described 35 my invention as applied to a cover for rolled materials, of course, it is equally applicable to articles of other form wherein it is desirable to protect the edges for any 40 purposes whatever.

In the drawings in which like characters relate to like parts; Figure 1 is a view of my improved cover; Figure 2 is an enlarged cross section on the line 2, 2, of Figure 1. 45 Figure 3 is a cross section thru a roll showing my cover in position. Figure 4 is an end view of a roll having my improved cover thereon.

The cover is preferably made of canvas, 50 cloth, burlap or similar suitable flexible material, and is longer than the circumference of the roll to be protected, and wider than the roll is long. A is the body portion of the cover, B is a reinforcement of material much heavier than A but preferably

also made of canvas, cloth, burlap or other suitable flexible material. The reinforcement B is so placed that it extends down over the fabric A a considerable distance and is stitched to the fabric A by suitable stitching C. The free edge of material B is folded upon itself at D the free edge portion E beyond the fold D being folded back on the fabric B and stitched thereto by stitching F so as to form longitudinally of the cover a pocket in which is placed a rope, twine or suitable fastening material G. This rope G is fixedly secured a little to one side of the longitudinal center of the cover at the point H, and near the end at 60 the point J the ends pass outward thru the pocket and are free to be used for the purpose of fastening the cover in position. A similar reinforcement provided with a similar pocket, and containing in the pocket 65 a similar rope for fastening the cover in place is attached along the opposite longitudinal side of the flexible material A. In attaching these reinforcements B to the flexible material A, I preferably have them 70 lap over the material A a considerable distance, so that when the cover is in place, the edges formed by the sides of the roll and the ends of the roll are protected by 75 two plies, the body material proper A, and the reinforcing material B. Arranged along the longitudinal edge of the reinforcing strip B are suitable openings I, so that 80 the rope, twine or other fastening may be drawn thru any one of the openings I, depending on the size of the roll to be covered. The rope, twine or other fastening G is also attached near the extreme end 85 within the pocket. This arrangement is made so that when the cover is in place on the roll if the roll is of less circumference 90 than the length of the cover, a workman in applying the cover draws the fastening means G out thru one of the openings I, which one depending on the size of the roll, 95 and attaches that loop portion to the end G. If desired, the fastening J could be dispensed with, and the workman thereby enabled to draw the fastening G out thru any 100 one of the openings and have the free end of the fastener for attachment to the opposite free end G. This would in that event leave a portion of the covering to the left of the illustration, as shown in Figure 1, without any attaching means and it would 105 110

either have to be folded or otherwise fastened in place or be left free. Without the fastening means J, the workman having used the cover on a small roll, would then 5 in order to use it on a large roll have to pass the fastener G again thru the pocket formed in the reinforcing strip. This of course would take time and I therefore prefer to fasten it at the point J. By having 10 it attached at the point J when a loop is drawn thru any of the openings, the free end of the cover material is gathered and automatically held in place without any additional fastening other than the mere tying 15 of the free end of the fastener G to the looped portion passing thru the openings I. As shown in Figure 3, the covering is in place around one end of a roll and a looped portion of the fastener G is ready for tying 20 with the free end of the fastener G. In Figure 4 an end view of a roll is shown, having the cover on, which illustrates how the one end of the cover is gathered automatically when the fastener G is drawn thru 25 one of the openings I.

I have shown in the drawings and described my improvement as a cover for protecting the edges of rolls or other products, but I would have it understood that it is 30 equally applicable for articles which may be of any form having edges desirable to protect. If desired a cover could be made of a material sufficiently heavy to serve the purposes and dispense with the reinforcement, 35 but in view of the fact that the wear and strain is along the edges of the product covered, and in view of the fact that the cover is primarily to protect the edges of a product, it is cheaper to use a lighter material 40 for the body portion of the cover and reinforce it with a heavier material along that portion that will come in contact with the edges of the product when it is in place on the article to be protected.

45 What I claim is:

1. A protective cover for articles adapted to cover the edges thereof, a pocket arranged along the edge of said cover, and a cord

member located within said pocket, adapted to hold the cover in position, said member 50 fixedly held within said pocket at the ends only of said pocket.

2. A protective cover for articles, having a pocket along the edge thereof, a cord member wholly located within said pocket between the ends of said cover, openings extending inward from the edge of said cover, to permit access to said cord member; means located beyond a plurality of said openings fixedly securing said cord member within 60 said pocket between said means so that cord member between said means is always of the same length as the distance between said means, all so arranged that when said cord member is looped through one of said openings it will gather the edge of said cover to 65 reduce its normal length.

3. A protective cover for articles comprising a body member, a pocket arranged in said body member, a plurality of openings 70 in said pocket, fastening means normally located wholly within said pocket, throughout the portion of length of said means corresponding to the length of the pocket, means fixedly securing said fastening means within 75 said pocket, all so arranged that a portion of said fastening means may be looped through one of said openings to use in fastening the cover in place.

4. A protective cover for articles comprising a body member, a pocket arranged in said body member, a plurality of openings in said pocket, fastening means normally located wholly within said pocket, throughout the portion of length of said means corresponding to the length of the pocket, a plurality of means fixedly securing said fastening means within said pocket at points beyond the openings, all so arranged that a portion of said fastening means may be 80 looped through one of said openings to use in fastening the cover in place.

In testimony whereof I have signed my name to this specification.

ALBERT E. F. MOONE.
